UNITED STATES PATENT OFFICE.

ROBERT R. WEAVER, OF COLUMBUS, OHIO, ASSIGNOR TO THE RALSTON STEEL CAR COMPANY, OF COLUMBUS, OHIO.

DROP-DOOR-OPERATING MECHANISM FOR CARS.

1,170,130.

Specification of Letters Patent.

Patented Feb. 1, 1916.

Application filed August 6, 1915. Serial No. 44,018.

To all whom it may concern:

Be it known that I, ROBERT R. WEAVER, a citizen of the United States, and a resident of Columbus, in the county of Franklin and State of Ohio, have invented certain new and useful Improvements in Drop-Door-Operating Mechanism for Cars; and I do hereby declare the following to be a full, clear, and exact description of the invention, such as will enable others skilled in the art to which it appertains to make and use the same.

This invention relates to drop door operating mechanism for dumping cars of the type shown in Patent No. 1,124,188 granted to me on the fifth day of January 1915, one object of my present invention being to improve and simplify the operating mechanism for drop doors and to so construct and arrange such simplified mechanism that it shall be disposed in a manner as to be operable at right angles to the line of motion of the car and thus reduce liability of being accidentally released by the longitudinal shocks due to sudden starting or stopping of the car.

A further object is to so construct the mechanism that a positive lock shall be provided for the door, without the use of pawl and ratchet means.

A further object is to construct the mechanism in such manner as to prevent shock or injury to the operator when the doors drop with a quick movement after the load starts to carry the doors downwardly.

With these and other objects in view, the invention consists in certain novel features of construction and combinations of parts as hereinafter set forth and pointed out in the claims.

In the accompanying drawings; Figure 1 is a plan view of a portion of the lower part of a hopper bottom car (fragmentary portions of the hopper body being shown) illustrating an embodiment of my invention; Fig. 2 is a view on the line 2—2 of Fig. 1; Fig. 3 is a view on the line 3—3 of Fig. 2; Fig. 4 is a view on the line 4—4 of Fig. 2; Fig. 5 is a separate view of one of the shafts 11, and Figs. 6 and 7 are detail views illustrating the clutch devices.

1, 1, represent the side sills and 2, 2, the draft sills of a car provided with a hopper body indicated at 3. Drop doors 4 are provided for the open bottom of the hopper body, and these doors are hinged at their upper

edges to brackets 5 secured to the hopper at the sides of the open bottom thereof, so that when released, said doors may swing toward the car sides. The doors are braced by means of bars 6 (which may be made in the form of I-beams) and these bars project beyond respective ends of the doors as indicated at 7 (as shown in Fig. 2) for a purpose herein-after explained. The draft sills 2, 2 of each pair terminate adjacent to the hopper body 60 and are spread apart as shown in Fig. 1 to accommodate parts of the door operating mechanism.

Near each end of the hopper body, brackets 8—9 are secured between the draft sills 70 and are made with inclined bearings 9—10 in which the end portions of inclined or diagonally disposed shafts 11 are mounted. An intermediate part of each shaft 11 is made angular in cross section and bent to 75 form an intermediate offset portion 12, as clearly shown in Fig. 5. To each shaft 11, at respective sides of the offset portion thereof, crank arms 13 are secured, and connected at their free ends by a wrist pin 14. 80 Two blocks 15 are loosely mounted on each wrist pin 14, and the upper ends of pitmen 16 are connected with said blocks by means of pivot pins 17 disposed at right angles to the wrist pin. The lower ends of the pitman 85 16 of each pair are loosely connected with the respective doors by means of links 18—19, the latter being secured to the projecting portions 7 of the door bars 6.

A worm wheel 20 is mounted loosely on 90 each inclined shaft 11 between bearing 10 and one of the crank arms 13. Transverse shafts 21—22 are mounted in suitable bearings 23 secured to the draft sills 2, and these shafts carry worms 24 to mesh with the 95 worm wheels 20,—said worms being properly spaced from the bearings 23 by means of sleeves 25. The transverse shaft 21 extends through both side sills 1, while the shaft 22 may be made shorter and extends 100 through one side sill only, and suitable bearing braces 26 are secured to the side sills for said transverse shafts. The two transverse shafts are provided with sprocket 105 wheels 26^a connected by a sprocket chain 26, so that when one of said shafts is operated, motion will be also imparted to the other, and the projecting ends of both transverse shafts are adapted for the reception of a suitable manually operable device. 110

Lost-motion or clutch devices are provided between each worm wheel and the adjacent crank arm 13, and comprise a lug 27 on the hub portion of the crank arm, 5 movable in a segmental recess 28 in the hub portion of the worm wheel and coöperable with the ends of a lug 29 which constitute the ends of said segmental recess.

When the doors are closed, the mechanism 10 will assume the positions shown in Figs. 2, 3 and 4 of the drawings,—in which positions, the pitmen will be disposed in the offset portions 12 of the crank shafts 11, and the connections of said pitmen with the 15 wrist pins will be so disposed with respect to the axes of the crank shafts that a positive lock to retain the doors in closed position will be provided; and it is apparent that the greater the load is upon the doors, 20 the more effectual will be the locking action above described. When the transverse shafts are turned, the coöperation of the clutch members will cause the crank shafts to turn sufficiently to overcome the locking action 25 above described, whereupon the load will force the doors open and during such opening movement, the lugs 27 of the clutch devices carried by the crank arms, will move freely through the segmental recess 28 of 30 the clutch members carried by the worm wheels,—thus permitting the doors to drop forcibly without danger of back-lash on the gearing or injury or shock to the operator.

Various changes might be made in the 35 details of construction of my invention without departing from the spirit thereof or limiting its scope and hence I do not wish to restrict myself to the precise details herein set forth.

Having fully described my invention, 40 what I claim as new and desire to secure by Letters Patent, is:—

1. The combination with a car and two drop doors therefor, of an inclined crank 45 shaft disposed approximately in line with the axis of the car, pitman connections between said crank shaft and each of said drop doors, and means for operating said crank shaft.

50 2. The combination with a car body and two drop doors therefor, of an inclined shaft disposed approximately in line with the axis of the car, two crank arms rigid with said shaft, a wrist pin connecting said 55 crank arms, pitman connections between said wrist pin and both of said doors, and means for operating said shaft.

3. The combination with a car body and two drop doors therefor, of a centrally located inclined crank shaft, pitman connections between said crank shaft and both of said drop doors, a worm-wheel loose on said shaft, lost-motion clutch devices between said worm-wheel and said crank shaft, a transverse manually operable shaft, and a 60 worm carried by the transverse shaft and meshing with said worm wheel. 65

4. The combination with a car body and two drop doors therefor, of a centrally located shaft, crank arms rigid therewith, a wrist pin connecting said crank arms, pitman connections between said wrist pin and the respective drop doors, a worm loose on said shaft, said worm-wheel and one of the crank arms carrying coöperating lost-motion clutch devices, a transverse shaft, and a worm carried by said transverse shaft and meshing with said worm wheel. 75

5. The combination with the framework, a car body and drop doors for the latter, of an inclined crank shaft supported by the framework approximately in line with the axis of the car, pitman connections between said crank shaft and the respective drop doors, said crank shaft having an offset portion 80 to receive said pitman connections and effect a lock for the drop doors, and manually operable means for operating said shaft. 85

6. The combination with the framework, a car body and two drop doors for the car 90 body, of centrally located inclined crank shafts near respective ends of the body, pitman connections between each crank shaft and the drop doors, gearing for operating both crank shafts, and lost-motion clutch devices between said gearing and the crank shafts. 95

7. The combination with the framework, a car body and two drop doors therefor, of a centrally located inclined shaft, crank 100 arms rigid with said shaft, a wrist pin connecting said crank arms, two blocks mounted on said wrist pin, pitmen loosely connected with the respective doors, and pivot pins disposed at right angles to said wrist pin 105 and connecting the pitmen with the respective blocks on the wrist pin.

In testimony whereof I have signed this specification in the presence of two subscribing witnesses.

ROBERT R. WEAVER.
